UNITED STATES PATENT OFFICE.

NATHAN GOLDSMITH, OF NEWARK, NEW JERSEY, ASSIGNOR TO L. GOLDSMITH & SON, OF NEWARK, NEW JERSEY, A FIRM COMPOSED OF DAVID OSTERWEIL, NATHAN GOLDSMITH, SYDNEY OSTERWEIL, AND LEON OSTERWEIL.

DESIGN FOR A BRACKET FOR WARDROBE-TRUNKS.

48,177.

Specification for Design.

Patented Nov. 23, 1915.

Application filed July 26, 1915. Serial No. 42,097. Term of patent 14 years.

To all whom it may concern:

Be it known that I, **NATHAN GOLDSMITH**, a citizen of the United States, residing at Newark, in the county of Essex and State of New Jersey, have invented a new, original, and ornamental Design for a Bracket for Wardrobe-Trunks, of which the following is a specification, reference being had to the accompanying drawing, forming part thereof.

The single figure of the drawing is a perspective view of a bracket embodying my invention.

I claim:

The ornamental design for a bracket for wardrobe trunks, as shown.

NATHAN GOLDSMITH.
